UNITED STATES PATENT OFFICE.

ALBERT LIVINGSTON BLACKMAN, OF LONDON, ENGLAND.

HYDRAULIC COMPRESS.

SPECIFICATION forming part of Letters Patent No. 431,738, dated July 8, 1890.

Application filed October 1, 1889. Serial No. 325,640. (No model.)

To all whom it may concern:

Be it known that I, ALBERT LIVINGSTON BLACKMAN, a citizen of the United States, at present residing at London, in England, have 5 invented certain new and useful Improvements in or relating to Hydraulic Compresses, of which the following is a specification.

My invention relates to improvements in the manner of constructing and economically 10 and expeditiously operating hydraulic compressors especially applicable to the compression of cotton, wool, jute, flax, hemp, and other materials; and it consists, principally, in the manner of constructing an economical 15 and powerful compress; also in employing compressed air and water or other fluid under pressure in such a manner as to store and preserve the power employed as the actuating motor or agent for operating the compress, so as to secure a quick, prompt, responsive 20 action as contradistinguished from the sluggish action usual in such motors; also by the utilization of the elasticity of the air to prevent a shock and incidental evil consequences resulting therefrom.

In the accompanying drawings, Figure 1 is a view of my compress forming part of a bale-compress car. Fig. 2 is a plan of a bale-compress-car platform constructed of a series of 25 accumulator-tubes and having a central opening, showing in horizontal cross-section the pendent supporting suspender or stirrup, movable hydraulic cylinder and stationary tubular piston-rod of the bale-compress, and 30 the duct in the said piston-rod for the passage of the actuating-fluid. Fig. 3 is a side elevation of my stationary bale-compress, showing the power-accumulators, fluid-reservoir, force-pumps, connecting-pipes, and lifting-cranes. 35 Fig. 4 is a plan of the same.

Like letters indicate corresponding parts.

A is the rectangular frame of a bale-compress-car bed, preferably constructed of metal, strongly constructed and mounted on 40 trucks adapted to travel on railways, whereby it may be moved about from point to point where needed. This car-bed has a substantially-framed opening A³ near its center, passing completely through it, and adapted to re-

ceive and accommodate the operation of the 50 bale-compress B.

C C' are series of cylindrical tubes arranged parallel to each other, wholly within and forming the entire top of said car-bed, except the opening A³. The tubes C C' are arranged 55 longitudinally with the car-bed, to which they tend to give greater strength and stability, and are connected with each other and with force-pumps D D', fluid-reservoir tanks d d', and the hydraulic cylinder b⁴, by induct 60 and educt pipes having suitable valves, as hereinafter pointed out, and they are adapted to serve as power-accumulators for the air and fluid-power motors, respectively. Over the foundation formed by the series of accumula- 65 tors C C', if desired, may be adjusted a flooring A² to give the workmen operating the compress a better footing.

b b are two heavy substantial vertical up-right standards or brackets, rigidly secured 70 at their lower ends to the car-bed on opposite ends of the central opening A³ and above to a cross-head s, formed on the stationary upper compressor-platen b', whereby a substantial rigid foundation and framing is provided for 75 sustaining the strain, and within which the bale-compress may be operated. The upper side of cross-head s on stationary platen b' is slightly arched, as seen in Fig. 1, and has a curved groove or channel in its sides and upper edge for engaging with and sustaining the endless supporting stirrup or suspender b², and is adapted to resist and sustain the upward pressure from the movable bale-compressor platen below.

b² is a powerful nearly oval-shaped or oblong endless metal suspender or stirrup, having on its interior vertical edges ways or channels for the guides b⁶, formed on the movable lower compress-platen to prevent the latter from being displaced. This suspender or stirrup is adjusted in the groove in the cross-head s, and upper or stationary platen b' hangs pendent between the vertical standards or brackets b and down through the opening A³ in 95 the car-bed, and receives and supports in its lower end the stationary piston-ram b⁵ and the combined movable hydraulic cylinder b⁴.

and bale-compress platen b^3 , and is adapted to support the strain of compressing bales under great pressure. b^5 , serving both as piston and piston-rod, has a circular head with a 5 slightly concave face with an outlet, is supported on a hollow vertical shaft b^8 , having lateral openings, (inlet n and outlet n'), and terminates in a projecting curved yoke or seat b^7 , provided with a groove or channel in its outer edge for receiving, and is adapted to engage with, rest on, and be supported in the lower end of the endless suspender or stirrup, b^2 in such a manner as to freely oscillate in its seat to allow the platen-face to adjust 15 itself automatically to the inequalities of a bale while being compressed. The ends of said curved yoke are so extended as to afford a rest for the cylinder b^4 when in repose. The piston b^5 , the vertical hollow piston-rod b^8 , 20 and the curved yoke or seat b^7 , having upward-projecting ends, are preferably cast in one piece with gussets b^9 , and so that the extreme ends of the yoke b^7 will form a rest for the lower edge of the hydraulic cylinder b^4 . 25 b^4 is a cylinder open below, having an interior convex head, and is adapted to receive and work on the stationary piston b^5 , and is designed to serve as a movable hydraulic cylinder, and carries on its outer upper face a 30 bale-compress platen b^3 , preferably part of the same, and is guided in its vertical motions by the guides b^6 , moving in ways or channels on the inner edges of the endless suspender or stirrup b^2 . The upper face of the 35 piston b^5 is formed concave, so that the fluid used as a motor agent may be all readily drawn off and leave no sediment to wear the cylinder, and the opposing working-face of the cylinder-head is preferably formed correspondingly 40 convex, so as to minimize the space to be charged with the motive agent and obtain a prompt response and maximum results.

The pressure-accumulators $C C'$, as shown in Fig. 2, are series of tubes properly connected together so as to form a substantial body and platform to the car-bed, of which it becomes part, serving to stiffen and strengthen the structure, and receives the motor-fluid under pressure through conduit-pipes $i i'$, 45 (shown in dotted lines,) respectively, from force-pumps $D D'$. The pumps $D D'$ draw the liquid which they displace respectively from the tanks d and d' , through pipes i^2 and i^3 , respectively, and the said pumps may be operated by steam supplied through the pipe d^4 50 from a boiler specially provided for the purpose, or preferably from the boiler of the locomotive, by which the apparatus is transported from place to place, or from any other 55 suitable source; or instead of by steam they may be operated by any other suitable motor agents.

The pipe d^4 is provided with suitable couplings or valves d^5 to enable the connection 60 with the steam-generator to be made at either end of the car, the valves at the end not so connected being shut off.

d^2 is a branched pipe for conducting the exhaust-liquid from the cylinder of press B to the tanks d and d' , d^3 , Fig. 2, being a valve 70 by which such exhaust may be controlled. Instead of the two tanks d d' , only one may be employed.

c is a pipe for conducting fluid under the pressure from the accumulators C to the cylinder b^4 , and c' is a pipe for similarly conducting fluid under pressure from the accumulator C' to the said cylinder. 75

c^2 and c^3 are valves by which admission to the cylinder b^4 of the liquid under pressure 80 may be controlled. The pipes c c' are connected to the passage in b^8 in any suitable and convenient manner. The valves c^2 , c^3 , and d^3 are preferably connected by links, rods, levers, and the like to hand-levers F , by which 85 they may all be operated from the same spot.

This compress may be located on any suitable fixed foundations, and in detail construction, arrangement, and connection is similar to that already described, the only points of difference being that the relative location of the various parts is modified, and that one of the tanks d d' may be omitted and but one tank be used in regulating the supply of fluid to the pumps respectively. 90

The manner of operating the apparatus is as follows: First, to initially charge the accumulators $C C'$, air is forced into said accumulator-tubes under pressure by the air-pump G , through connecting-pipes $f f'$, having suitable valves o o' , and when the desired degree of air-pressure in the accumulators $C C'$ is attained the air-pump is cut off by the valves o o' and stopped. The fluid-pumps $D D'$ are then set to work, the valves in their connecting-pipes are opened, and water, oil, or other suitable liquid is forced into said accumulators under great pressure, thereby further compressing the air until the desired pressure in the accumulators is secured, at which point there may be an arrangement to automatically "cut off" and stop the pumps. The valve connecting said accumulators $C C'$ with the hydraulic cylinder is then opened and the elasticity of the air expels the fluid from the accumulators into the hydraulic cylinder, thereby imparting action and force to the bale-compress. Whenever the pressure falls below the pressure desired, the pumps automatically commence to work again and continue to augment and restore the power stored in the accumulators. In this arrangement the accumulators $C C'$ may be conveniently placed above the floor X or in any out-of-the-way place that may be accessible. When it is desired to compress a bale, the accumulators and pressure-reservoirs are charged as heretofore described, the platen b^3 being in its lowest position. The uncomressed bale is placed thereon by the crane E or by any other means, 110 the exhaust-valve d^3 is closed, the pressure-valves c^2 and c^3 are opened, respectively, one after the other, so that by the elasticity of the air the liquid is forced from the accumu- 115

120 125 130 135

lators C C' under great pressure, through the hollow vertical stationary piston-rod b^8 of the stationary piston b^5 into the movable hydraulic cylinder b^4 between the piston b^5 and the head of the cylinder b^4 , thereby forcing the lower compress-platen b^3 , carrying the uncompressed bale upward against the stationary platen b' with force sufficient to compress the bale into the dimensions desired. The bale is then hooped or bound in any of the usual ways, and the valves c^2 and c^3 turned off and the exhaust-valve d^3 opened. The platen will then descend by its own weight and that of the bale, and the liquid from within the cylinder will be forced through the passage in b^8 and exhaust-pipe d^2 back into the tanks d and d' .

I claim—

1. In a bale-compressor, the movable hydraulic cylinder open below and having a bale-compressor platen on its upper face and adapted to adjust and work on and in combination with stationary piston, and having side guides, stationary piston having a concave face and central opening, hollow vertical stationary piston-rod having lateral openings at its base for the passage of actuating-fluid, curved yoke having upward-projecting ends and provided with a channel or groove through which it is secured in its seat in pendent endless suspender or stirrup, and a suspender or stirrup, all constructed and arranged substantially as described.

2. In a bale-compress, a combined movable compress-platen and hydraulic cylinder open below, in combination with a stationary piston with a concave face and central opening, having a stationary hollow piston-rod with lateral openings for the passage of actuating-fluid and terminating in a curved yoke, having upward-projecting ends and grooved on its lower edge for adjusting on and engaging with pendent endless suspender or stirrup, oblong endless suspender stirrup, upper combined cross-head and stationary platen, and supporting - brackets, substantially as described.

3. In a hydraulic power cylinder or bale-compress, a stationary piston-rod, the latter having a curved grooved base, through which it is secured in its seat in the endless suspender or stirrup pending from the stationary platen above, and a central vertical channel for the passage of the actuating-fluid, and the piston having a slightly - concaved face, in combination with a movable cylinder terminating at the upper end in a face to serve as a bale-compress platen, and a pendent suspender or stirrup, substantially as described.

4. In a bale-compress, the combination of the combined movable compress-platen and hydraulic cylinder formed in one piece, the latter open below and adapted to adjust on and be operated by a stationary piston, a stationary piston having a hollow piston-rod with induct and educt lateral openings and

terminating in a curved yoke or base, having a longitudinal groove or channel for engaging with pendent suspender or stirrup, an oblong supporting endless suspender or stirrup, the latter adjusted in a groove or channel in the upper cross-head, and a stationary platen, substantially as described.

5. In a bale-compress operated by hydraulic pressure, the combination of a combined movable compress-platen and hydraulic cylinder in one piece, the latter open below and adapted to work on a stationary piston, the stationary piston with a concave face and central opening, and having a hollow cylindrical piston-rod terminating in a curved yoke, having a groove in its lower edge for engaging with an oblong endless suspender or stirrup, and stationary platen and cross-head provided with a curved groove for receiving the endless suspender or stirrup, of the endless suspender or stirrup, of the pressure-reservoirs, and pipes connecting the same with force-pumps and with the hydraulic cylinder, substantially as described.

6. In a hydraulic bale-compress, a combined movable platen b^3 and hydraulic cylinder b^4 , open below and adapted to adjust and work on a stationary piston, stationary piston b^5 , with concave face, and having a hollow stationary vertical piston-rod b^8 , with lateral induct and educt openings n and n' , respectively, curved yoke, of seat b^7 , having a longitudinal groove or channel in its lower edge for engaging with the endless oblong suspender or stirrup b^2 , stationary platen b' , and cross-head s , supporting-brackets b , reservoirs d and d' , connecting-pipes c c' , force-pumps D D' , and connecting-pipes i i' , constructed and arranged substantially as described.

7. In a hydraulic bale-compress, a combined movable presser-platen b^3 and hydraulic cylinder b^4 , open below, stationary piston b^5 , formed together with stationary piston-rod b^8 and supporting-yoke b^7 , endless suspender or stirrup b^2 , stationary platen b' , and grooved arched cross-head s and supporting-brackets b , in combination with accumulators C C' , force-pumps D D' , supply-tanks d d' , and connecting-pipes provided with suitable valves, all constructed and arranged substantially as described.

8. In combination, the rectangular framing of the car-body, having a central opening, the tubular accumulators securely arranged parallel therewith and to each other and forming the car-body and platform or car-bed, the flooring laid thereon, the bale-compress secured within and supported by brackets rigidly secured to said car-bed, partly within said central opening, the force-pumps, supply-reservoirs, connecting-pipes, and movable hydraulic cylinder for compressing bales, substantially as described.

9. The combination of the rectangular framing of the car-body, the tubular accumula-

tors secured within and extending longitudinally of the same to form additional girders, and having the central opening of the brackets secured rigidly on each side of the opening, and the platens and plunger working between said brackets, substantially as described.

In testimony whereof I have hereto set my hand in the presence of two subscribing witnesses.

ALBERT LIVINGSTON BLACKMAN.
